X 6943 Claim of George Bettie, Township of the
Salters' District

The Schedule referred to in these Sallers' Patent and making part of the same contains a description in the words of the said David C. Crary himself of his improvement in portable Electric Power.

To all to whom these present shall come Be it known that, I, George Bettie, a citizen of the County of Clark and State of Ohio have invented a new and useful improvement in portable Electric Power and that the following is a full and exact description of the construction and operation of the said machine, as invented and improved by me. Performance is necessary of about the following dimensions. Specific weight of stranding cable 1000 pounds per cubic foot, and thickness 1/8 of an inch, being 1/8 of a mile of the same size and 1 foot inches long.

Two long side plates in the centre about one foot apart at the two ends and inclined at the other. The two short ones placed at the outside of the ends and about three inches apart from the outside to the inside.

Two pieces 8 inches by 16 are set on edge near the end of the short plates and one inch in all four sides and fastened down by bolts. One pair of timbers 8 inches by ten is laid flat under last described pieces lengthwise with the ends with the one edge even with the centre of the space between the long sides. Upon this same edge (top) are placed to receive the neck of the short shaft and immediately below a piece of wood about 16 inches long 16 inches wide and 4 inches thick is turned in the middle with a step of the short shaft.

Upon the short shaft between the step and the neck the horse-shoe is placed which is made of cast iron 6 feet in diameter the rim 8 inches wide with legs on the under side. Upon the top of the horse-shoe is placed a cast flange 6 feet in diameter which is formed in the following manner.

A plate of 3/8 of an inch thick of the diameter above mentioned and two pieces rising 2 inches above the plate and of the thickness of 3/4 of an inch and this plate parallel with each other leaving 1/4 inches of the centre of the plate between them other other pieces of the same description being at right angles with these leaving the

100

same space. The edge of the plate of the lower truck is raised to the same height on each segment of the circle. So that when a similar plate with the other side up is placed opposite to this one and fastened with four bolts on to each segment appears to form one solid circular wheel of 84 inches in thickness 2 feet in diameter with 14 metal 3 1/4 inches square at equal distances from each other and radiating from the top towards the centre of the wheel to receive the lances to which the horses are attached.

The length of the lances are about 11 feet 6 inches with a brace from one to another near the middle. The horses which stand before these lances will be about 3 feet 9 inches long mounted at the lower end to the diameter of the wheel to fit the stop in which it stands, 4 inches square up to the neck which is rounded to the diameter of 14 inches and 4 inches long. 1 inch square about the neck and tapering to 3 1/4 inches at the top which fits to a hole of this size in the centre of the flange. 1 1/2 inch of wrought iron 8 inches in diameter 10 feet 6 inches in length and another one ready in a piece of about 10 1/2 inches in diameter will always stand to work on the edge of the stock wheel both of which wheels are fixed. But the other end of this shaft is a second smaller wheel 4 feet in diameter.

This shaft is placed between the two long shafts and the 4 feet wheel turned in a frame fastened in the end of the shaft. A curved piece of metal 16 inches broad is fastened near each end of this frame leaving sufficient space between them for the four feet wheel to turn; and extending up to a proper height to receive a cap of 24 inches thick 10 inches and turned on them through the centre of this cap a hole is made to receive the ratchet pinion of about 9 inches in diameter. The jaws of the cap of this wheel and the one in which it works are 2 1/2 inches in length.

This wheel (the ratchet wheel) exhibits a plane surface on the one side with the exception of a hole in the centre of about 1 1/4 inch in diameter, on the other side the diameter of the opening is about 8 1/2 inches, and above half of an inch from the surface the metal is turned to a concave at nothing more than a project of an inch toward or toward the centre from the circle before there turned forming four stops or catches at equal distances from each other and standing 1 1/2 inch nearer the centre on the other side is an inch thick. A small circular piece of metal is an inch thick with a hole of 1/8 inch in diameter in the centre to enable to fill the ratchet pinion. It is intended these catches 1 1/2 feet apart to make 4 inches in diameter and the side thick with a hole in the centre 1 1/4 inches wide and a project

887 X 2 (347)

360

round the centre of the diamond frame above it, are such in width and by in depth
of holes are drilled through the edges of the piece
at equal intervals. These holes of no depth iron is an inch square by inches long
with a hole drilled through the one end through which and the holes in the edges of the
piece woods are forced, when each of these holes is placed a small slot opening which
leads to throw the one end out about an inch beyond the edge of the piece.

This is then placed in the cavity of the wheel last above
mentioned in such position that the ends of the last mentioned holes bear against
the ends of the four wooden spokes. The wheel itself construction is placed on
the centre of the inner surface of the shape of about 16 inches long and 14 in diameter
and is prevented from turning on that shape by a small groove made on the side
of the shaft and in the inner part of the inner wheel which is filled by a wedge.

The advantage of a wheel of this construction is that
if the horses start to stop while the machine is in rapid motion, the inner part of
the wheel would run around the machinery until its force is spent thereby
giving the work from the injury which might be sustained by a sudden stop.

By means of a universal joint attached to the
last mentioned wheel. This machinery may be conveniently applied to threshing
meat, cutting, sawing, Ginning, Drying, turning, &c &c. The purpose
superservus may be found in and proportioned to suit the labour for which
it is intended to be applied.
